UNITED STATES PATENT OFFICE.

JOHN R. TUCKER, OF BAXTER SPRINGS, KANSAS.

RIBBON-CASE.

SPECIFICATION forming part of Letters Patent No. 352,500, dated November 9, 1886.

Application filed August 27, 1885. Serial No. 175,468. (No model.)

To all whom it may concern:

Be it known that I, JOHN R. TUCKER, a citizen of the United States, residing at Baxter Springs, county of Cherokee, and State of Kansas, have 5 invented certain new and useful Improvements in Ribbon-Cases, of which the following is a specification, reference being had therein to the accompanying drawings.

This invention relates to ribbon-cases, and 10 it has for its objects means to provide a more convenient and simplified method of showing and displaying ribbons in an open glass-front show-case, and measuring the ribbons without removing them from the case.

15 Figure 1 represents a front view of the case. Fig. 2 represents a view of the back of the case, and Fig. 3 represents a transverse sectional view of the case from top to the bottom with the ribbons.

20 Fig. 1 is a front view of the case open, ready to receive the stock. The letter *a* represents the perpendicular space on each side for holding and displaying the reserve stock, the ribbons being piled one upon the other until

25 the space is filled. The letter *B* represents the rods in groups of three, constituting the shelf upon which the rows of ribbons are displayed, and from which they are measured by passing the end through slot *A* in Fig. 2. Upon the 30 back of the case, near each slot *A*, is secured a ring, *X*, to which the hook *A'* on the yard-stick *C* is attached when it is desired to measure the ribbons as they are drawn out through the slots in the back of the casing. The letter *C* in Fig. 1 represents the division between the 35 shelves and perpendicular spaces.

Fig. 2 represents the back of the case with open slots *A*, through which the ribbon is drawn for measurement.

40 Fig. 3 represents a section side view of the case from top to the bottom, showing the ribbons (marked letter *D*) as they are displayed

in the shelf *B*, ready for measurement. The letters *B* represent the groups of three rods each, forming the shelves upon which the 45 ribbons on the shelves are displayed. The letter *d* represents the end of the ribbon *D* passing through the slot *A* in Fig. 2. Letter *C* represents the yard-stick hooked to the ring *X*. The letter *H* represents the front 50 and the letter *S* the back of the case.

The frame-work of the case is composed of wood and metal, and put together with nails, screws, and glue. The doors are of glass, put together with wood and metal frames and facings. The rods are of wood and metal and fastened to letter *C* in Fig. 1.

Being aware that it is not new to attach tape-measures to ribbon-cases permanently by means of a ring placed upon the end of the 60 measure and sliding upon a horizontal rod secured upon the casing, I do not claim such construction as my invention.

Having thus described my invention, what I claim, and desire to secure by Letters Patent, 65 is—

In a ribbon case, the combination, with the casing having an open front and a transversely-slotted back, the ribbon-shelves each composed of a group of three horizontal rods, *B*, the spaces 70 *H* upon each side of the display-shelves for the reception and display of the reserve stock, and the rings *X*, secured upon the back of the casing near each of the horizontal slots therein, of the yard-stick *C*, provided with the hook *A'* so as to be detachably connected to any one of the rings *X*, substantially as shown and described.

In testimony whereof I affix my signature in presence of two witnesses.

JOHN R. TUCKER.
